SUBSCRIPTION TELEVISION DECODER

Melvin H. Boldt, Glenview, Ill., assignor to Zenith Radio
Corporation, a corporation of Delaware

Filed Oct. 20, 1960, Ser. No. 62,545

Term of patent 14 years

(Cl. D26—14)

FIGURE 1 is a perspective view of my design for a subscription television decoder;

FIGURE 2 is a front elevational view thereof;

FIGURE 3 is a side view thereof; and

FIGURE 4 is a sectional view as seen from line 4—4 of FIGURE 2.

The side not shown is the same as the side shown and the back is plain and unornamented.

The dominant features of my design reside in those portions of the drawing shown by means of full lines.

I claim:

The ornamental design for a subscription television decoder, substantially as shown and described.
